ARRANGEMENT FOR REDUCING CASE RESONANCE

Raymond L. Dills, Erie, Pa., assignor to General Electric Company, a corporation of New York

Application April 5, 1954, Serial No. 421,127

9 Claims. (Cl. 230—232)

This invention relates to hermetically sealed compressors and, more particularly, to an arrangement for damping case resonance of hermetically sealed internally sprung mounted high speed compressors.

Hermetically sealed compressors are sometimes required to operate in locations where the noise level is low, and it is desirable to eliminate or minimize all noises produced by the normal operations of the compressors. High speed compressors produce more noise than low speed compressors of similar construction and the difference in the noise level between a high speed compressor and a low speed compressor may render the high speed compressor objectionable if the noise from the interior of the casing and the resonance of the casing are not reduced. The case resonance of the high speed compressor is due, in part, to the driven noise that comes through the compressor casing.

The present invention reduces the case resonance of a high speed compressor until it is not an objectionable factor and the present invention also reduces the driven noise that comes through the compressor casing.

A primary object of the present invention is to provide an arrangement for reducing the resonance of the casing of a hermetic compressor.

An object of the invention is to provide a sound deadening arrangement for a hermetic compressor that is inexpensive.

A further object of this invention is to provide an arrangement for deadening the sound that is transmitted through the casing of a high speed hermetic compressor due to the operation of the high speed compressor.

Further objects and advantages of the invention will become apparent as the following description proceeds and the features of novelty which characterize the invention will be pointed out with particularity in the claims annexed to and forming a part of this specification.

This invention relates to a hermetic compressor including a sealed casing. Resilient means are disposed on the outside of and engaging the casing to deaden sound from the casing. A metallic member is placed in contact with each resilient means to aid the resilient means in deadening sound. Suitable means are provided to hold the sound deadening means including both the resilient means and the metal member in contact with the casing with a predetermined elastic force.

For a better understanding of the invention reference may be had to the accompanying drawing, in which:

Fig. 1 is an elevational view of a casing of a hermetic compressor embodying the present invention; and

Fig. 2 is a sectional view taken along the line 2—2 of Fig. 1.

Referring to the drawing, there is shown a casing 1 of a hermetic compressor. This casing is formed of two sections 2 and 3. The section 2 has a flange 4 extending completely around its periphery and the section 3 has a similar flange 5 extending around its periphery. The casing is formed by permanently joining the flanges 4 and 5 together to form a sealed casing. Since the

2

particular contents of the casing 1 do not form a part of the present invention, the details of the parts within the casing 1 are not shown but it will be understood that there is disposed within the casing 1 a compressor and a motor for driving the compressor. The gas to be compressed enters the casing 1 through suction line 6 and the compressed gas leaves the casing through exhaust line 7. Suitable lines 16 and 17 extend through the section 3 of the casing 1 to permit the cooled lubricating oil to enter the casing and the hot lubricating oil to leave the casing.

Four resilient members 8 are disposed in contact with the exterior of the casing 1 across the center line C/L of the casing. These resilient members 8 are disposed above and below the flanges 4 and 5 of the compressor casing 1 as shown in Fig. 2. A metallic member 9 is placed in contact with each of the resilient members 8 (see Fig. 2) to aid the resilient member 8 in reducing the noise resulting from case resonance and the noise being transmitted from the interior of the casing. The metallic members 9 are held in contact with the resilient members 8 and the resilient members 8 and the metallic members 9 are held in the desired position extending for equal distances on each side of the center line C/L by suitable means such as a strap 10. The ends of this strap are joined together by a suitable fastening means 11 such as a clamp similar to the signode type of fastener. The tension in the strap 10 aids in the sound damping by exerting a force on the resilient members 8 and the metallic members 9.

The resilient member 8 is preferably a butyl rubber pad that has holes punched therein to soften the rubber. The metallic members are preferably steel blocks or bars. In one embodiment of this invention the bars are about three inches long by one inch wide and one-quarter inch to one-half inch deep. However, the particular size of the members, the softness or thickness of the rubber, and the tension of the strap must be carefully chosen to obtain the optimum acoustic damping for the particular casing with which it is to be used. These characteristics will vary according to the size of the casing.

It will be observed that the metallic members 9 are of less width than the resilient members 8 but that the metallic members 9 have a greater depth than the resilient members 8. If desired, the metallic members may have one edge in contact with the flange 4 or the flange 5 of the casing 1. While the member 8 has been designated as being resilient and the member 9 as being metallic, it will be understood that other suitable materials could be employed if desired. It will be understood that the term "sound from the casing" employed in the claims includes both the noise resulting from the resonance of the casing and noise transmitted from the interior of the casing.

While the present invention has been described by reference to a particular embodiment thereof, it will be understood that modifications may be made by those skilled in the art without actually departing from the invention. I, therefore, aim in the appended claims to cover all such variations as come within the true spirit and scope of the foregoing disclosure.

I claim:

1. A hermetic compressor including a sealed casing, said casing being formed of two sections permanently joined together, a plurality of resilient members disposed in contact with the exterior of said casing to deaden sound from said casing, a metallic member in contact with each resilient member to aid said resilient member in deadening sound, each of said resilient members being of the same size, each of said metallic members being of the same size, each of the resilient and metallic members being disposed across the center line of the casing, said members

extending for equal distance on each side of the center line of the casing, and means to hold the resilient members and the metallic members in position, said holding means aiding in deadening sound.

2. A hermetic compressor including a sealed casing, said casing being formed of two sections permanently joined together, a plurality of resilient members disposed in contact with the exterior of said casing to deaden sound from said casing, a metallic member in contact with each resilient member to aid said resilient member in deadening sound, each of said resilient members being of the same size, each of said metallic members being the same size, each of the resilient and metallic members being disposed across the center line of the casing, said members extending for equal distance on each side of the center line of the casing, said resilient members having a greater width than said metallic members, and means to hold the resilient members and the metallic members in position, said holding means aiding in deadening sound.

3. A hermetic compressor including a sealed casing, said casing being formed of two sections permanently joined together, a plurality of resilient members disposed in contact with the exterior of said casing to deaden sound from said casing, a metallic member in contact with each resilient member to aid said resilient member in deadening sound, each of said resilient members being of the same size, each of said metallic members being the same size, each of the resilient and metallic members being disposed across the center line of the casing, said members extending for equal distance on each side of the center line of the casing, said metallic members having a greater depth than said resilient members, said resilient members having a greater width than said metallic members, and means to hold the resilient members and the metallic members in position, said holding means aiding in deadening sound.

4. A hermetic compressor including a sealed casing, said casing being formed of two sections, each of said sections having a flange extending around its periphery, said sections being permanently joined together along said flanges, a plurality of resilient members disposed in contact with the exterior of said casing to deaden sound from said casing, said resilient members being disposed adjacent said flanges, a metallic member in contact with each resilient member to aid said resilient member in deadening sound, each of said resilient members being of the same size, each of said metallic members being of the same size, each of the resilient and metallic members being disposed across the center line of the casing, said members extending for an equal distance on each side of the center line of the casing, and means to hold the resilient members and the metallic members in position, said holding means aiding in deadening sound.

5. A hermetic compressor including a sealed casing, said casing being formed of two sections, each of said sections having a flange extending around its periphery, said sections being permanently joined together along said flanges, a plurality of resilient members disposed in contact with the exterior of said casing to deaden sound from said casing, said resilient members being disposed adjacent said flanges, a metallic member in contact with each resilient member to aid said resilient members in deadening sound, each of said resilient members being of the same size, each of said metallic members being of the same size, each of the resilient and metallic members being disposed across the center line of the casing, said members extending for an equal distance on each side of the center line of the casing, said resilient members having a greater width than said metallic members, and means to hold the resilient members and the metallic members in position, said holding means aiding in deadening sound.

6. A hermetic compressor including a sealed casing, said casing being formed of two sections, each of said sections having a flange extending around its periphery, said sections being permanently joined together along said flanges, a plurality of resilient members disposed in contact with the exterior of said casing to deaden sound from said casing, said resilient members being disposed adjacent said flanges, a metallic member in contact with each resilient member to aid said resilient members in deadening sound, each of said resilient members being of the same size, each of said metallic members being of the same size, each of the resilient and metallic members being disposed across the center line of the casing, said members extending for an equal distance on each side of the center line of the casing, said resilient members having a greater width than said metallic members, said metallic members having a greater depth than said resilient members, and means to hold the resilient members and the metallic members in position, said holding means aiding in deadening sound.

7. A hermetic compressor including a sealed casing, said casing being formed of two sections permanently joined together, a plurality of members disposed in contact with the exterior of said casing to deaden sound from said casing, a second member in contact with each of said first members to aid said first member in deadening sound, each of said first members being of the same size, each of said second members being of the same size, each of said first and second members being disposed across the center line of the casing, said members extending for an equal distance on each side of the center line of the casing, and means to hold said first members and said second members in position, said holding means aiding in deadening sound.

8. A hermetic compressor including a sealed casing, said casing being formed of two sections permanently joined together, a plurality of members disposed in contact with the exterior of said casing to deaden sound from said casing, a second member in contact with each of said first members to aid said first members in deadening sound, each of said first members being of the same size, each of said second members being of the same size, each of said first and second members being disposed across the center line of the casing, said members extending for an equal distance on each side of the center line of the casing, said first members having a greater width than said second members, and means to hold said first members and said second members in position, said holding means aiding in deadening sound.

9. A hermetic compressor including a sealed casing, said casing being formed of two sections permanently joined together, a plurality of members disposed in contact with the exterior of said casing to deaden sound from said casing, a second member in contact with each of said first members to aid said first member in deadening sound, each of said first members being of the same size, each of said second members being of the same size, each of said first and second members being disposed across the center line of the casing, said members extending for an equal distance on each side of the center line of the casing, said first members having a greater width than said second members, said second members having a greater depth than said first members, and means to hold said first members and said second members in position, said holding means aiding in deadening sound.
